BINDER LOCKING MECHANISM

Edward A. Koelling, St. Louis, Mo.

Application November 8, 1939, Serial No. 303,347

2 Claims. (Cl. 129—23)

The present invention relates generally to loose leaf binders, and more particularly to a locking mechanism for post binders.

An object of the present invention is to provide a novel locking and release mechanism, finding particular adaptation to post binders.

Another object is to provide a novel locking mechanism which may be employed with post binders having a wide range of post diameters.

Another object is to provide a novel locking mechanism which may be employed with post binders, the posts of which are of varying distances apart.

Another object is to provide a novel floating locking mechanism which includes means for preventing dislocation of the working elements.

Another object is to provide a novel locking mechanism which includes means for firmly gripping smooth or annularly recessed binder posts.

Another object is to provide a novel locking mechanism of general adaptation to post binders.

Another object is to provide a novel locking mechanism for post binders which is simple in construction, easy to install, simple to manipulate, and positive in action.

Other objects and advantages will be apparent from the following description, taken in conjunction with the accompanying drawings, in which:

Fig. 1 is a top view of a non-protruding post binder, the upper casing of which is adapted to receive an embodiment of the present invention, parts being broken away;

Fig. 2 is an end view of the non-protruding post binder shown in Fig. 1;

Fig. 3 is an enlarged view of the casing of the non-protruding post binder shown in Fig. 1, disclosing a preferred embodiment of the present invention installed therein, the elements thereof being in post-gripping relationship, parts of the case being broken away for purposes of clarity;

Fig. 4 is a section through the case of the cover of the illustrated post binder showing the preferred embodiment of the present invention located therein in released relationship;

Fig. 5 is a section on the line 5—5 of Fig. 3;

Fig. 6 is a section on the line 6—6 of Fig. 3;

Fig. 7 is a section on the line 7—7 of Fig. 3;

Fig. 8 is a section on the line 8—8 of Fig. 6;

Fig. 9 is a section on the line 9—9 of Fig. 3;

Fig. 10 is a perspective view of a carrier element of the present locking mechanism;

Fig. 11 is a perspective of the post-engaging element of the present locking mechanism;

Fig. 12 is a plan view of one of the locking

assemblages in engagement with an ungrooved binder post;

Fig. 13 is a section on the line 13—13 of Fig. 12; and,

Fig. 14 is a view of a slightly modified locking assemblage.

Referring to the drawings more particularly by reference numerals, there is disclosed a non-protruding post binder generally designated 20 which includes an upper case 21, an upper cover 22, upper hinge elements 23, loose leaves 24, a lower case 25, a lower cover 26, lower hinge elements 27, and two spaced posts 28 and 29. The cases 21 and 25 are shown as uncovered for simplicity. The posts 28 and 29 are anchored in the lower case 25 and extend into, but not through, the upper case 21 through suitable apertures 30. Each of the posts 28 and 29 includes an annular groove 32 near the upper end in a position to lie wholly within the upper case 21 (Fig. 6).

Within the case 21 is a locking mechanism of the floating type generally designated 35. A shaft 36 extends longitudinally of the case 21 which includes a reduced extremity 37, a threaded segment 38, and a squared extremity 39 (Fig. 4). The threaded segment 38 may be of substantial extent in order to accommodate the locking mechanism to varying spaces between binder posts.

A locking assemblage generally designated 40 is rotatably mounted on the reduced extremity 37 of the shaft 36 and includes a carrier or rider 41 (Fig. 10) and a post-engaging element 42 (Fig. 11).

The rider 41 includes a flat body 45 and right-angularly extending flanges 46 which are curved at each end 47 to conform to the curved ends of the case 21. Aligned apertures 48 extend through one end of the flanges 46. A notch 49 is in the free edge of each of the flanges 46, being disposed in aligned relationship. There is a slot 50 in the body 45 which extends in the direction of the aligned apertures 48.

The post-engaging element 42 includes a segment 52 and a segment 53 disposed at an angle. A slot 54 is disposed through the segment 52 and extends longitudinally thereof. Projections 55 extend from the sides of the segment 52 at substantially the juncture of the segments 52 and 53. The segment 53 includes a V-notch 56, the defining walls of which are at an angle to the plane of the segment 53, a relationship which can be grasped through an inspection of Figs. 6 and 11. The sharp edges effected through the

walls of the notch 56 comprise the post-contacting portions of the post-contacting element 42.

The post-engaging element 42 is disposed in engagement with the rider 41, with the projections 55 abutting one flange 46 adjacent the notch 49 and with the segment 53 disposed in the notch 49 (Fig. 7). The fit of the parts is snug, so that this fit together with the snug fit of the assemblage 40 in the case 21 causes the element 42 to remain in the aforesaid position in the rider 41.

The extremity 37 of the shaft 36 extends through the aligned apertures 48 in loose relationship, the inward flange 46 abutting a washer 58 which, in turn, abuts the shoulder formed at the juncture of the reduced extremity 37 and the main body of the shaft 36. A second washer 59 is disposed adjacent the outer face of the other flange 46, the end of the reduced extremity 37 being peened over to prevent removal of the washer 59. The shaft 36 is thus rotatable relative to the locking assemblage 40, although there is no relative longitudinal movement.

A second locking assemblage 60 (Fig. 4) is threadedly mounted on the threaded segment 38 of the shaft 36. The locking assemblage 60 is identical in every respect with the locking assemblage 40, except the aligned apertures 48 are threaded and, therefore, requires no particular description.

The locking mechanism 35 is disposed within the case 21 in the manner shown in Fig. 4 with the locking assemblage 40 disposed adjacent the post 28 and the locking assemblage 60 disposed adjacent the post 29. A rivet 64 extends through the aligned slots 50 and 54 of each of the locking assemblages 40 and 60 and is anchored in the opposed sides of the case 21.

The squared extremity 39 of the shaft 36 extends into adjacent relationship with an aperture 61 in an end cap 62 to receive a key 63. A rider 65 of the same configuration as that of the rider 41 is disposed about the end of the shaft 36 adjacent the squared extremity 39, being maintained in this position by an indentation 66 in the case 21 (Fig. 4). The rider 65 maintains that portion of the shaft 36 adjacent the squared extremity 39 in alignment.

In Fig. 14 there is shown a modified locking mechanism 35' wherein the locking assemblage 40' is in threaded relation with a threaded portion 67, the aligned apertures 48' having left-hand threads. The other elements of the locking mechanism 35' are the same as in the locking mechanism 35 previously described.

In Figs. 12 and 13 there is disclosed a post 29' which is ungrooved. The V-notch 56 of the segment 53 has engagement with the full diameter of the post 29'. The remaining elements of the disclosure are the same as previously described.

Operation

The assembly of the present device is apparent from the foregoing detailed description, taken in conjunction with the accompanying drawings. It is sufficient to state that the locking mechanism 35 is disposed in the case 21, as shown in Fig. 4, with the locking assemblage 40 disposed to be adjacent the post 28 and the locking assemblage 60 disposed to be adjacent the post 29. The rivets 64 provide a floating relationship between the locking mechanism and the case 21. After the leaves 24 have been disposed about the posts 28 and 29, the case 21 is disposed over the upper ends of the posts 28 and 29. The manipulation

of the key 63 rotates the shaft 36 to force the locking assemblages 40 and 60 into engagement with the posts 28 and 29, inasmuch as the locking assemblage 60 rides along the shaft 36 by virtue of its engagement with the threaded segment 38. The V-notches 56 of the locking assemblages 40 and 60 engage the walls of the grooves 32 in binding relationship to maintain the case 21 and its associated cover 22 in operative disposition.

The shaft 36 is under considerable strain when the locking mechanism 35 is in locking engagement, so that there is a tendency to bend. The rider 65 prevents the end of the shaft 36 adjacent the squared extremity 39 from bending out of alignment, so that the squared extremity 39 is always accessible by the key 63.

Release of the locking mechanism 35 is accomplished by rotating the shaft 36 in a direction contrary to the rotation required to effect locking. The floating arrangement of the locking mechanism 35 permits the drawing of the locking assemblage 40 inwardly, due to longitudinal movement of the locking assemblage 60.

The walls of the V-notch 56 of each of the locking assemblages 40 and 60 permit gripping engagement of the post-engaging element 42 with a smooth post in the manner shown in Figs. 12 and 13. The edges of the V-notch 56, in effect, bite into the wall of the smooth post.

Both of the locking assemblages may have threaded engagement with the shaft, if desired, as shown in Fig. 14. This construction is advantageous for certain installations.

It is apparent that the locking assemblages 40 and 60 are of simple yet unique construction. The post-engaging element 42 may be disposed in either direction across the rider 41 to dispose the segment 53 in the notch 49 of either flange 46. It becomes unnecessary, therefore, to have right- and left-hand elements. Where both of the locking assemblages 40 and 60 threadedly engage the shaft 36, it is necessary to have right-hand and left-hand threaded aligned apertures 48, but each rider 41 may be provided with two pairs of aligned apertures of reverse threading, if desired.

The present invention may be employed with a non-protruding post binder, as shown, or it may be used with binders having protruding posts. It is effective with both stationary and flexible posts. The V-notch 56 of each of the locking assemblages 40 and 60 is of a construction to accommodate itself to a wide range of post diameters.

The particular configuration of the several elements of the present device may be changed within the scope of the present invention. Each of the elements is, of course, constructed from suitable material, the post-engaging elements being preferably case-hardened.

It is apparent that there has been provided a device which fulfills all of the objects and advantages sought therefor. It is to be understood that the foregoing description and accompanying drawings have been given by way of illustration and example, and not for purposes of limitation, the invention being limited only by the claims which follow.

What is claimed is:

1. In a device of the kind described, a locking mechanism for post binders disposed within a case including a shaft disposed longitudinally within the case, spaced members within the case connected to said shaft, one of said members being threadedly connected to said shaft for

movement therealong, the other of said members being connected to said shaft to permit rotative movement of the shaft, each of said members including a carrier and a post-engaging element disposed in fixed relationship to each other when assembled, said post-engaging element being removable from the carrier, said carrier being of a configuration to receive said post-engaging element in positions at 180° to each other, each of said members being adjacent a binder post, and means to rotate said shaft to move said post-engaging elements into and out of engagement with the binder posts.

2. In a device of the kind described, a locking mechanism for post binders disposed within a case including a shaft disposed longitudinally within the case, spaced members connected to

the shaft to permit rotation of said shaft, each member being disposed adjacent a binder post, each member including a carrier connected to said shaft and a post-engaging element, said carrier being of inverted U configuration, each leg of said carrier being of a configuration to snugly fit within the case and having a wide notch in the free edge, said post-engaging element being in the configuration of an obtuse angle, the apex of which is disposed in one of the notches of the carrier, said element having a notch in the outermost free edge adapted to engage a binder post, and means to rotate said shaft to force said members into binding contact with the binder posts.

EDWARD A. KOELLING.
